SEAL FOR CASED WELLS

Robert R. Thompson, Marshall, Mo.

Application February 24, 1948, Serial No. 10,522

11 Claims. (Cl. 285—22)

1

My invention relates to well seals, and more particularly to a seal for a cased well, such as a water well.

One of the purposes of my invention is to provide a fluid tight seal between a well casing and a fluid conduit, such as a water conduit, that is mounted within the casing and in spaced relation to the casing, as is customary in water wells and similar wells that are provided with metallic casings. In wells of this character the casing may extend to or slightly above the ground level and before the seal is applied has an open end, into which the fluid conduit extends. While means have been provided previously for closing the space between the upper end of the well casing and the conduit within the same, none of the means previously provided have been successful in preventing entrance of water and other matter into the interior of the casing. Anything that enters the interior of the casing will pass into the water standing therein, from which the water is drawn that passes through the fluid conduit, and will contaminate it. Accordingly it is highly important to provide a fluid tight seal between the upper end of the well casing and the tubular fluid conduit within the same so as to maintain a water supply that is not contaminated by any surface water or other matter that might enter through the top of the casing. My improved sealing means provides an absolutely fluid tight seal between the upper end of the casing and the tubular conduit within the same so as to prevent any entrance of contaminating material to the well within the casing.

It is another important purpose of my invention to provide such a tight seal between the well casing and the tubular conduit within the same that air will not even enter into the space between the casing and the well tubing or similar fluid conduit so that a pressure below atmospheric will develop in the casing upon pumping operations being carried out, which will tend to raise the water level to such an extent that a greater flow of water can be obtained than would be true if such a reduction in pressure were not developed.

It is a further purpose of my invention to provide a well seal that prevents any upward movement of the fluid conduit in the well, there being a tendency in some wells for this to take place because of the fact that the pump is on the bottom end of the fluid conduit and the pump has a tendency to rise in the body of water in the well. By my improved well sealing means the seal is fixed to the casing so that no upward

2

movement of the seal relative to the casing will take place and the fluid conduit is secured to the sealing means in such a manner that it will be held from upward movement relative to the sealing means, thus preventing any upward movement of the pump or any other parts connected to said conduit.

My invention is applicable to wells that are provided with either a single fluid conduit or a pair of such conduits, such as used with jet type pumps, the principle of operation of my sealing means being the same no matter whether one or more fluid conduits are provided inside the well casing.

15 Other objects and advantages of my invention will appear as the description of the drawings proceeds. I desire to have it understood, however, that I do not intend to limit myself to the particular details shown or described, except as defined in the claims.

In the drawings:

Fig. 1 is a vertical sectional view through the upper end portion of a well casing and showing fragmentary portions of a fluid conduit mounted within said casing and extending upwardly therefrom, showing my improved sealing means applied thereto.

Fig. 2 is a view partly in top plan and partly in section, taken on the line 2—2 of Fig. 1.

Fig. 3 is a view similar to Fig. 1 of a modification, and

Fig. 4 is a view similar to Fig. 1 of a further modification.

Referring in detail to the drawings, my improved well seal is shown as being applied, in Fig. 1, to a well having a tubular metallic casing 5 within which is mounted centrally a fluid conduit 6, which may have any suitable means within the same for operating a pump, which is not shown, the pump being understood to be on the lower end of the tubular member 6 so as to supply liquid from the well through said pipe or tubing 6. In the application of my improved well sealing means to a well having such a casing 5, the upper end of the casing is belled or flared out as shown at 7 by suitable means. However, prior to such flaring or bellng out of the upper end portion of the casing 5, a ring 8 of steel is applied to the casing, said ring having an opening therein so as to freely receive the casing 5 below the balled out portion 7 thereof. The ring 8 is provided with a circular series of bolt openings 9 therein and a steel plate 10, which is of a disk-like character, as will be evident from Fig. 2, is applied to the top edge 11 of the well casing 5.

Said plate-like member is, preferably, of the same external diameter as the ring 8. Said ring 8 has a beveled or inclined face 12 that is directed toward the plate-like member 10 and a circular series of openings 13 is provided in the plate-like member 10 that align with the openings 9 and bolts 14 are mounted in the aligning openings 9 and 13 and have nuts 15 applied thereto.

The plate-like member 10 has a reinforcing plate 4 welded fluid tight thereto and said plate 10 and plate 4 are provided with central aligning openings therein, which have internal threads 16. A threaded nipple 17 has its external screw-threads engaging the threads 16 so as to secure the nipple fluid tight to the plate-like member 10 and plate 4, the plate 4 being provided to increase the length of the screw-threaded connection securing said nipple 17. A pipe coupling 18 connects the nipple 17 with the tubular conduit 6 and a similar tubular conduit 19 is connected with the nipple 17 through a coupling 20 for providing an upward extension of the fluid conduit 19 to any suitable point above the top of the casing 5, to which said liquid may be carried for supplying any suitable apparatus or for storage, said coupling 20 being screwed down tight against the top surface of the reinforcing plate 4.

An annular gasket 21 of compressible material, such as rubber, is mounted between the upwardly and outwardly inclined surface of the bell portion 7 of the well casing 5 and the downwardly and inwardly inclined surface 12 of the ring-like member 8. It will be obvious that a wedging action will take place between the inclined surface 12 of the ring-like member 8 and the bell portion 7 of the well casing, and between said inclined surface 12 and the inner face of the plate-like member 10 and compress the gasket into the shape shown in Fig. 1 of the drawings so as to completely seal the space between the plate-like member 10, the flared or bell end 7 of the casing 5 and the ring 8 when the nuts 15 are tightened up on the bolts 14.

Inasmuch as the plate-like member 10 will thus be sealed in fluid tight relation to the well casing 5 and the threaded connections between the members 10, 17, 18 and 6 will also provide a fluid tight connection between the fluid conduit 6 and the plate-like member 10, a fluid tight seal will be provided between the upper end of the casing and the tubing or fluid conduit within the same, this seal being so complete that when pumping takes place within the well to pass liquid upwardly through the conduit 6, the pressure in the space 22 between the casing 5 and the conduit 6 will be reduced below atmospheric pressure, which will have a tendency to cause the casing 22 to fill to a higher level with water than would otherwise be the case, thus increasing the rate of flow of a well that is sealed in this manner. Also, no matter how near the ground level or surface the upper end of the casing 5 may be, no polluted water or other undesirable contaminated material will enter a well that is provided with a seal of this character.

In Fig. 3 a slight modification of my invention is shown, in which the casing 5 is flared in the same manner as previously described and has the same compressible annular sealing member provided between the ring-like member 8, which is made in the same manner as previously described, and a plate-like member 10', which is the same as the plate-like member 10, except that the central opening 23 therein has a pipe coupling 24 ex-

tending therethrough and welded in position therein, the internal weld being indicated by the numeral 25 and the external weld by the numeral 26. The other parts of the seal being the same as previously described, have the same reference numerals applied thereto as in Figs. 1 and 2, and the sealing means for providing the fluid tight seal between the upper belled end of the casing 5 and the ring-like member 8 and the disk-like plate 10' operates in precisely the same manner as above described. However, the fluid conduit 6 is connected directly with the coupling 24 and the upwardly extending fluid conduit 19 is similarly directly connected with the coupling 24.

In assembling either of the above described well seals, the ring 8 and the annular gasket 21 are placed in position before the well casing is flared out, as indicated at 7 in both Figs. 1 and 3. Then the fluid conduit or tubing 6 within the well is connected with the plate-like member 10 either through the nipple 17 and coupling 18, or by means of the coupling 24, after which the bolts 14 are inserted in the aligning openings in the members 10 or 10', as the case may be, and the ring 8, and the nuts 15 applied to draw the ring 8 toward the plate-like member 10 or 10' to compress the annular gasket 21. While the annular gasket 21 is, preferably, of a somewhat triangular shape in cross section before being compressed, if made of suitable compressible material, the exact cross sectional shape is not so important, because under the high pressure exerted by the multiplicity of bolts used and the wedging action of the surface 12 and the outer inclined face of the bell portion 7, the gasket 21 will assume a shape such as to completely fill the space between the two wedging surfaces and the adjacent undersurface of the plate-like closure member, as shown in Figs. 1 and 3.

While the seal is shown in Figs. 1 to 3, inclusive, as being applied to a well that has a single pipe or fluid conduit within the same, either form of the invention above illustrated can be provided with plate-like members having more than one opening therein for a plurality of fluid conduits, should this be found desirable. Such an arrangement is illustrated in Fig. 4, in which the ring-like member 8 is the same as previously described and is applied to the casing 5 having the flared or belled out portion 7 in the same manner as previously described, the same reference numerals being applied to these parts as in the other forms of the invention. However, the plate-like member 10'' is provided with a plurality of openings instead of a single opening, two openings being shown. This plate-like member is clamped to the ring 8 to compress the gasket 21 in the same manner as previously described, by means of the bolts 14 and nuts 15, which pass through the aligning openings 9 and 13. The plate-like member 10'' is provided with a pair of openings 27 therein that have the fluid conduits 28 connected therewith in liquid tight relation, this being shown in Fig. 4 as being accomplished by providing couplings 29 that are welded by means of internal welds 30 and external welds 31 to the plate-like member 10'' to provide a liquid tight connection between said couplings and the plate-like member. The threaded ends 32 of the tubular conduits 28 are connected with the couplings on the lower side of the plate-like member 10'' and upward extensions 33 thereof are connected with the couplings 29 to extend above the plate-like member 10''. The arrangement shown in Fig. 4 is provided,

for example, where a jet type of pump is utilized for pumping the water from the well.

In all forms of the invention the same advantages exist in connection with the seal, that is, that the space 22 will have a reduction of pressure below atmospheric develop therein as the pump operates, to thus increase the flow of water into said space within the casing 5, thus increasing the flow of the well. Also, no matter whether one or more fluid conduits are provided in the casing so as to extend within the same and upwardly above the upper end thereof, an absolute fluid tight seal is provided between the open upper end of the casing 5 and such conduit or conduits.

It will be noted that the plates 10, 10' and 10'' are, preferably, made of a heavy gauge steel so as to have sufficient strength to support the fluid conduits that are secured thereto and any apparatus that may be connected with said fluid conduits within the casing 5, and that said plate-like members are firmly supported on the upper end edge of the casing. It will further be noted that in case there is any upward force acting on the tubular member or members within the casing this will be transferred through the plate-like member 10, 10' or 10'' to the ring 8, which is also made of heavy gauge steel, and from said ring to the flared or belled out portion 7 of the casing, thus preventing any upward movement of said fluid conduits relative to the casing 5. Furthermore, due to the fact that the ring-like member 8 of the disk-like members 10, 10' and 10'' are made of steel plate, a very great amount of the pressure can be exerted on the gasket member 21 by means of the bolts 14 and nuts 15, being only limited by the possibility of the stripping of the threads on the bolts or nuts, which will not occur in practice because of the fact that a large number of said bolts and nuts are utilized for securing the parts in position.

What I claim is:

1. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member, a sealing gasket of compressible material mounted between said ring and plate-like member and engaging said casing, clamping means engaging said ring and plate-like member to compress said gasket between said casing, plate-like member and ring, said plate-like member having an opening therein, and means mounted in said opening and extending therethrough, said means having a liquid tight connection with said plate-like member and said conduit to provide a liquid tight connection between said plate-like member and said conduit.

2. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member, said casing member having an annular abutment provided thereon adjacent said end, an annular gasket of compressible material mounted between said ring and plate-like member and engaging said abutment, clamping means engaging said ring and plate-like member to compress said gasket between

said abutment, plate-like member and ring, said plate-like member having an opening therein, and means mounted in said opening and extending therethrough, said means having a liquid tight connection with said plate-like member and said conduit.

3. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member, said casing being flared at said end to form an annular abutment thereon, a sealing gasket of compressible material mounted between said ring and plate-like member and engaging said flared portion of said casing, clamping means engaging said ring and plate-like member to compress said gasket between said abutment, plate-like member and ring, said plate-like member having an opening therein, and means mounted in said opening and extending therethrough, said means having a liquid tight connection with said plate-like member and said conduit to provide a liquid tight connection between said plate-like member and said conduit.

4. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member, a sealing gasket of compressible material mounted between said ring and plate-like member and engaging said casing, clamping means engaging said ring and plate-like member to compress said gasket between said casing, plate-like member and ring, said plate-like member having an opening therein, and a tubular threaded member mounted in said opening in fluid tight relation to said plate-like member, said fluid conduit being detachably connected thereto.

5. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member having an annular wedging face thereon, an annular sealing gasket of compressible material mounted between said annular wedging face and plate-like member and engaging said casing, clamping means engaging said ring and plate-like member to compress said gasket between said annular wedging face, said plate-like member and said casing, said plate-like member having an opening therein, and means mounted in said opening and extending therethrough, said means having a liquid tight connection with said plate-like member and said conduit to provide a liquid tight connection between said plate-like member and said conduit.

6. A well seal comprising a disk-like member having an opening therein, a tubular threaded member mounted in said opening in fluid tight relation to said disk-like member, said tubular member having threaded portions extending beyond the opposite faces of said disk-like member, a ring having an inclined annular inner sur-

face thereon, an annular compressible gasket mounted between said inclined annular surface and a face of said disk-like member and clamping means engaging said ring and disk-like member to secure said ring to said disk-like member and compress said gasket between said disk-like member and inclined surface.

7. A well seal comprising a disk-like member having a central opening therein, a tubular threaded member mounted in said opening in fluid tight relation to said disk-like member, said tubular member having threaded portions extending beyond the opposite faces of said disk-like member, a flat ring having an inclined annular inner surface thereon, an annular compressible gasket mounted between said inclined annular surface and a face of said disk-like member and clamping means engaging said ring and disk-like member to secure said ring to said disk-like member and compress said gasket between said disk-like member and inclined surface.

8. A well seal comprising a disk-like member having a pair of openings therein, a tubular threaded member mounted in each of said openings in fluid tight relation to said disk-like member, said tubular members having threaded portions extending beyond the opposite faces of said disk-like member, a ring having an inclined annular inner surface thereon, an annular compressible gasket mounted between said inclined annular surface and a face of said disk-like member and clamping means engaging said ring and disk-like member to secure said ring to said disk-like member and compress said gasket between said disk-like member and inclined surface.

9. A well seal comprising a disk-like member having a threaded opening therein, a tubular member mounted in said opening, said tubular member having external threads thereon engaging the threads in said opening and extending to the opposite ends thereof, said threaded ends extending beyond the opposite faces of said disk-like member, a ring having an inclined annular inner surface thereon, an annular compressible gasket mounted between said inclined annular surface and a face of said disk-like member and clamping means engaging said ring and disk-like member to secure said ring to said disk-like member and compress said gasket between said disk-like member and inclined surface.

10. A well seal comprising a disk-like member having an opening therein, a tubular member welded in said opening in fluid tight relation to said disk-like member, said tubular member having internally threaded portions extending beyond the opposite faces of said disk-like member, a ring having an inclined annular inner surface thereon, an annular compressible gasket mounted between said inclined annular surface and a face of said disk-like member and clamping means engaging said ring and disk-like member to secure said ring to said disk-like member and compress said gasket between said disk-like member and inclined surface.

11. The combination with a well casing and a fluid conduit extending within said casing in spaced relation thereto, of means providing a liquid tight seal between the upper end of said casing and said conduit comprising a plate-like member engaging said end of said casing, a ring surrounding said casing in spaced relation to said plate-like member, said ring having an annular wedging face thereon and said casing being flared at said end, an annular sealing gasket of compressible material mounted between said wedging face and plate-like members and engaging said flared portion of said casing, clamping means engaging said ring and plate-like member to compress said annular gasket between said wedging face, said plate-like member and flared portion, said plate-like member having an opening therein, and a tubular member mounted in said opening in fluid tight relation to said plate-like member and extending beyond both faces of said plate-like member, the portion of said tubular member extending below said plate-like member being threaded for connecting said fluid conduit thereto.
